US0D1090224S

(12) **United States Design Patent** (10) **Patent No.:** **US D1,090,224 S**
(45) **Date of Patent:** **** Aug. 26, 2025**

(54) **KEY**

(71) Applicant: **Guangxi Gaixie Electronics Co., Ltd.**,
Guigang (CN)

(72) Inventor: **Junhua Wu**, Guigang (CN)

(73) Assignee: **Guangxi Gaixie Electronics Co., Ltd.**,
Guigang (CN)

(**) Term: **15 Years**

(21) Appl. No.: **29/995,255**

(22) Filed: **Mar. 25, 2025**

(30) **Foreign Application Priority Data**

Dec. 3, 2024 (CN) 202430767300.7

(51) **LOC (15) Cl.** **08-07**

(52) **U.S. Cl.**

USPC **D8/347**; D8/312

(58) **Field of Classification Search**

USPC D8/300, 307, 310, 311, 312, 321, 322,
D8/330, 331, 347

CPC E05B 1/0053; E05B 1/0007; E05B 17/00
